(54) CORN SHELLING

(76) Inventor: Isaac A. Hedges

Isaac A. Hedges, Elmira, N. Y.,
Lettins Patent

The schedule referred to in these Letters Patent and making part of the same, containing a description in the words of the said Isaac A. Hedges himself of his improvement in the machine for shelling corn.

To all to whom these presents shall come, Where it is known that I Isaac A. Hedges of Elmira in the County of Tioga and State of New York, have invented a new and useful machine for corn shelling and that the following is a full and exact description of the construction and operation of the said machine as invented by me. A box of about ten feet in height having the two sides of timber or plank bolted to posts, and these also bolted to cross planks which form the two ends. The sides are parallel to each other and upright ends ^{the} inclining a little towards each other being further apart at the bottom. Upon the middle of the sides of this box are placed the ends of a horizontal iron shaft which projects a few inches beyond each side, and is sunk into each side about half its diameter. The shaft thus lies about two feet from the bottom of the box. This shaft passes through the centers of the two ends of a cylinder of about twenty inches in length and eight in diameter. The sides of the box being of sufficient distance apart to permit the cylinder to revolve freely between them. To one end of this shaft is fixed a balance wheel of iron or other material of from fifty to seventy five pounds in weight which together with the cylinder revolves with the shaft and is designed to give steadiness and momentum to the revolutions of the cylinder. To one arm of this wheel about half way from its centre to its circumference is fixed a handle for the purpose of being moved by hand. The wheel is about thirty inches in diameter. To the other extremity of the shaft is fixed a small wheel also revolving with it about which a strap may be passed for the purpose of connecting it with such machinery as may be suitable for moving the cylinder by horse, steam or

waterhouse. When this is done, the iron frame is used, the baton which may if judged necessary be disengaged from the shaft. The cylinder is formed of cast iron tubes. Upon its concave surface are shallower tubercles of about one fourth of an inch in height arranged at moderate intervals in parallel rows at short distances from each other each row consisting of two lines as nearly straight as may be inclining towards the direction in which the cylinder recedes meeting midway between the two ends of the cylinder and forming there an angle of about one hundred and fifty degrees with each other. The iron tubes which form the surface of the cylinder are secured by a wrought iron band passing round the ends of the cylinder. A concave iron vessel cylindrical in surface lying horizontally and having its upper edges in the same horizontal plane. This surface is of sufficient extent to cover nearly the whole of the lower half of the cylinder and when in its natural position the space between the cylinder and that edge of the surface at which the ears of iron are in order to form between them the cylinder is about one and one fourth inches gradually diminishing till at the opposite edge when the ears leave the cylinder this space is about five eighths of an inch. The space of them mentioned are reckoned from the general surface of the cylinder to the summit of the ridge to be described in the concave surface. And these spaces may be increased or diminished in proportion to the sizes of ears in different countries. This concave surface consists of two or more rectangular spaces each running the whole length of the cylinder and entailing a semicircular bar of iron bars made in a cast iron plate which is attached by bolts to the inside of the bars on each side. These plates also assist in forming a support to the shafts of the cylinder. A shaft one inch of the body of each sleeve is turned upwards to prevent behind the cast plates just mentioned thus preventing the heads of screws from interfering with the springs attached to the backs of the sleeves. These springs may be of wood or of steel and are about three fourths of an inch broad. If of wood one spring is attached to the back of each sleeve by screws and extends both ways dipping a little from the sleeve.

will be cut out the mortise at the end of the slats and rest on that side of the mortise which is further from the cylinder. On entering the mortise the space between the spring and the slats is about three-fourths of an inch. If of steel the arc attached, one now, each end of the slats entering the mortise in the manner. The concave surface will thus press the edge of each against the cylinder and at the same time spring back inwardly according to the different sides of the ears & at no time pressing with sufficient force to break the line of ears. These rectangular notches which form the concave surface are about three-eighths of an inch in thickness ^{strongly} by flanges offered to each edge of the slats and running along the length within the end plates, meet the edges of the mortise into which the slats enter and confine the slats to its proper place between the cast iron side plates. Each flange is about $\frac{1}{8}$ of an inch thick. Each flange projects about one eighth of an inch above that edge of the slat which is next the cylinder undulating three-fourths of an inch beyond the opposite side, thus strengthening this slat and forming a ridge in the concave surface. The breadth of each slat with the spring attached is about two inches. The slats are perforated with holes, the centers of which are about one inch apart, and sufficiently large to permit the hand of a workman to pass through. Openings are left for the same purpose between the side plates. These holes are made between the spring and flange and not directly above the spring. A second opening a hoffice and cover for the upper part of the cylinder is formed in the following manner. Two rectangular pieces of plank of about one foot in breadth and of sufficient length to fill the upper edge of the ears of the box before described, are joined together by two pieces of board so as to divide them, each other, into a hoffice in which to store the ears of ears. The opening at the lower part of this hoffice is about three inches in breadth and of a length nearly equal to that of the cylinder, being attached to the rectangular pieces of plank to admit the opening as to prevent the ears of ears from falling between the ears of the cylinder and the sides of the box. Having placed the two rectangular pieces of

placed upon the sides of the first described box in such a manner that the middle of these lance edges (ground, for the purpose,) falls to over the shaft of the cylinder. This opening of the hopper is about two or three inches above the cylinder. A piece of plank running from one of the before mentioned rectangular pieces of plank to the other and firmly fixed - having its inner surface adapted to a concave cylindrical, the said concave cylindrical surface being inclined as to have this surface parallel to that of the cylinder with sufficient space between to form the largest cap of concavity, between it and the cylinder. This surface covers one half of the upper half of the cylinder except the opening for the hopper. The other half of the upper part of the cylinder is covered by a piece of board running from one of the rectangular pieces of plank to the other serving as a door which opens upward and is kept open while the machine is in operation. This second box is fixed to the first box by a hook attached to the outside of each rectangular piece of plank and may be taken off at pleasure. The cylinder being put in motion it runs, from an air blow into the hopper by the hand or by a wheel and accompanied by the motion and the protuberances of the cylinder between that and the wheel now rotating just mentioned till they fill the space between the cylinder and the concave cylindrical surface just described. Bumping between this surface and the cylinder and rolled over by means of the protuberances in the cylinder and above mentioned ridge in this concave surface, they are rolled as they pass along this space, the kernels falling through the openings in and between the stars of this concave surface. The only flying out of the opposite sides of them as would otherwise happen in a violent vibration being turned from the machine by means of the above mentioned open door. The falling kernels are caught by two pieces of board of wood immediately under the concave surface and running from one side of the box to the other being so inclined as to cause the kernels to roll into a trough placed in the bottom of the box and extending from one side to the other. The bottom of the trough is a plank so inclined as to cause the kernels to

slide out of the box by an opening in the side of the box. This trough may be taken out of the box and placed within it in such a manner as to cause the kernels to fall out either side of the box at pleasure. — The said Isaac A. Hedges, claiming as his invention the concave cylindrical surface by a combination of sleeves with springs attached as herein described and the application of such surface in form to the surfaces of corn shelling and the application of such surface to a cylinder for the same purpose.
